UNITED STATES PATENT OFFICE

2,247,636

BOWLING ALLEY

Alfred H. Lewis, Lynn, Mass.

Application August 19, 1938, Serial No. 225,715

6 Claims. (Cl. 273—51)

This invention relates to bowling alleys and the method of making the same.

The present invention is particularly adapted for the construction of outdoor alleys for use at beaches and pleasure resorts where the alleys are often subjected to unfavorable weather conditions.

In alleys now in general use outdoors the changing weather conditions cause the boards forming the alley to warp and soon cause the alley to become useless.

The object of the present invention is to overcome this objection and produce an alley in which the body portion of the alley is protected by water-proof and impervious materials so that the alleys will not warp but remain in operable condition for a long period of time.

Another object of the invention is the construction of the alleys in sections whereby they may be carted from place to place and the sections tied together when a favorable site is found.

By making the alleys in sections it is possible in northern climates to disassemble the alleys and store them during the winter months and again assemble the sections in the spring at some selected point.

These objects are obtained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a side elevation of one part of a bowling alley embodying the principles of the present invention.

Figure 2 represents a side elevation of the other part of said alley.

Figure 3 represents a side elevation of a portion of the alley and showing the means for connecting together the adjacent ends of two sections thereof, said figure being drawn to an enlarged scale.

Figure 4 represents a plan of a plurality of said alleys, each alley being composed of a plurality of sections of equal length.

Figure 5 represents a transverse section of the

same on line 5, 5 on Fig. 4, drawn to an enlarged scale.

Figure 6 represents an enlarged detail on line 6, 6 on Fig. 4.

Figure 7 represents a horizontal section on line 7, 7 on Fig. 6.

Figure 8 represents an enlarged detail, on line 8, 8 on Fig. 1.

Figure 9 represents a plan of the frame work of one of the sections of the alley.

Figure 10 represents a side elevation of portions of two of the alley sections and showing the means for connecting them together end to end.

Figure 11 represents an enlarged transverse section through one of the alleys, and

Figure 12 represents an enlarged transverse section of a modified form of alley.

Similar characters indicate like parts throughout the several figures of the drawings.

10 In building the improved bowling alleys a plurality of frameworks are first formed, each consisting of side timbers 10, 10 and cross timbers 12, 12.

15 Centrally disposed between the side timbers 10, 10 and parallel thereto is a timber 11, the opposite ends of which are connected to the cross timbers 12.

20 At each end of this framework are diagonally disposed timbers 13, 13 bracing the framework and giving rigidity thereto.

25 All of these frameworks are made of the same width and the same length.

30 Each framework has superimposed thereon and secured thereto a roofing paper 14 which is impervious to moisture.

35 Over this roofing paper 14 are a plurality of boards 15 extending transversely of the framework and nailed to the timbers 10, 11.

40 Superimposed upon the boards 15 is a layer of water-proof composition 16.

45 When this water-proof composition 16 is spread over the boards 15 it is permitted to harden and then the upper surface thereof is leveled, sanded and afterwards polished.

50 On the sides of each framework are channel irons 17 extending nearly to the ends of the frameworks and secured to the timbers 10 by bolts 18.

55 The central timber 11 of each framework has a stiffening angle iron 19 secured thereto by means of screws 20.

When the frameworks have been covered as described they form a plurality of similar units which may be assembled as desired.

55 When the various units of each alley are placed

end to end as shown in Figs. 1, 2, 4 and 10 of the drawings, the opposite sides of the adjoining ends of the abutting frameworks have secured thereto splicing channel irons 21 by means of bolts 22.

The different alleys having the various sections thereof spliced together in the manner heretofore described are placed upon a plurality of stringers 23 superimposed upon a plurality of posts 24 driven into the ground 25 and preferably connected to each other by plates 26 as shown in Fig. 5 of the drawings.

One set of units 27 are placed at the head of the alleys and only a portion of the upper surface thereof is covered with the water-proof composition 16 as indicated at 28, the remaining upper surface of these particular units being covered with linoleum 29 or some similar material with the upper face thereof alined with the upper surface of the layer 28 of composition 16, as shown in Fig. 4 of the drawings.

These units 27 at the head of the alley provide a runway for the bowlers and the division between these units 27 and the other sections of the alleys in advance thereof is at the foul line.

At the rear ends of the alleys are platforms 30 for the pin boys, these platforms being at a lower level than the alleys as shown in Fig. 2 of the drawings.

These platforms 30 are supported on stringers 31 mounted upon posts 32 driven into the ground 25.

Between the various alleys and at the rear ends thereof are partitions or baffle boards 33 as indicated in Fig. 4 of the drawings, and these baffle boards 33 are covered with the same water-proof composition 16 as is spread over the upper surface of the boards 15 of the various alley units.

At the rear of the platform 30 and above the same is swingingly mounted a buffer 34 of usual construction.

Over the rear end of the alleys is an enclosure 35 which protects the pin boys during inclement weather. This structure 35 may be made in any convenient manner.

Depending from the upper portion of the enclosure 35 is a lamp 36 adapted to light up the pins 36x mounted upon the rear end of the alley.

In a similar manner the front end of the alley is provided with a covering 37 to protect the bowlers in inclement weather.

At the extreme outer sides of the alleys are gutters 38 which rest upon the stringers 23, these gutters having a gutter guard 39 extending upwardly from the outer side thereof.

Between every two adjacent alleys are disposed double gutters 40, 40 with a gutter guard 41 extending upwardly between the two gutters 40, all as shown in Fig. 5 of the drawings.

Between two of the adjacent alleys the gutter guard 41 has deep holes 42 formed therein, each hole being for the reception of the lower end of a Y-shaped metal structure 43, the upper end of which is above the upper end of the gutter guard 41 and has welded thereto two pipes 44 extending the length of each unit of the alley.

These pipes 44 form a ball race for the return of the used balls to the head of the alleys.

To the top of the gutter guard is secured a metal plate 45 having an opening 46 therein through which the lower end of the Y-shaped structure extends.

This plate tends to retain the Y-shaped structure 43 in vertical position and prevents any

wear upon the surface of the hole 42 in the gutter guard 41 which is constructed of wood.

Where the ends of the pipes 44 abut each other they are retained in alinement by a rod 47 inserted into the ends of the pipes 44, as shown in Fig. 3.

Where the various units of the alley abut, the space between these ends is preferably filled with the water-proof composition 16, as indicated at 48 in Figs. 1 and 2 of the drawings.

The space between the units at the foul line is not filled with composition 16.

In some cases it is desirable to use a modified form of supporting structure, as for instance, such as is shown in Fig. 12 of the drawings, in which side boards 49 are secured to the outer face of the timbers 10.

In this modified form of supporting structure, the framework 10, 11 and 12 has a thick layer of concrete 50 superimposed thereon and over the upper surface of this concrete is spread the water-proof composition 16.

By making bowling alleys in the manner shown and described the various units of the alleys may be moved from place to place and set up at any desired point.

If business gets slack at one point the units may be disassembled and moved to some other point where it would appear the business would be more profitable.

Moreover, the alleys are so constructed that the various units may be stored during the winter months and then set up at any convenient place in the spring.

When in use the coating of water-proof material covering the alleys prevents the alleys from warping and getting out of shape.

Moreover, by covering the under faces of the boards with water-proof roofing material, moisture is prevented from rising and affecting the boards.

This coating of water-proof composition 16 for the upper surface of the alleys is composed in part of wooden chips and sawdust and when hardened and polished makes an excellent surface for bowling.

The housings at the opposite ends of the alleys may be provided with side curtains if desired to protect the bowlers and pin boys from the glaring sun or strong winds.

The units 27 at the head of the alleys are entirely disconnected from the other units of the alleys, and as a consequence, any jar upon these units 27 caused by the bowlers running lengthwise thereof will not be transmitted to the units forming the main portions of the alleys.

It is believed that the operation and many advantages of the invention will be understood without further description.

Having thus described my invention, I claim:

1. A bowling alley comprising a supporting structure composed of a plurality of individual units, channel irons secured to the outer edges of the units forming the body of the alley and locking them in alinement with their ends slightly spaced apart, the flanges of said channel irons extending over upper and lower faces of said units, boards superimposed upon and extending transversely of each unit, and a level coating of hardened waterproof composition of equal consistency throughout superimposed upon and in contact with the upper surface of said boards and adhering thereto.
2. A bowling alley as set forth in claim 1, in which the under surfaces of said boards are

protected by sheets of impervious material in direct contact with said under surfaces.

3. A bowling alley as set forth in claim 1, in which the individual units in the body of the alley are secured together end to end with the spaces between the adjacent ends of said units filled with portions of said composition.

4. A bowling alley as set forth in claim 1, in which an additional unit is disposed at the head of the alley and is disconnected from the units conforming the body of the alley.

5. A bowling alley as set forth in claim 1, in which the channel irons enclose the opposite side edges of the individual units in the body of the

alley, said channel irons being secured to the adjacent ends of each pair of units.

6. A bowling alley comprising a supporting structure composed of a plurality of horizontally disposed individual units, channel irons secured to the outer edges of the units forming the body of the alley and locking them in alignment, transversely disposed boards superimposed upon each unit, and a continuous waterproof covering superimposed upon and directly in contact with the upper surface of said boards and adhering thereto.

ALFRED H. LEWIS.
